UNITED STATES PATENT OFFICE.

HERBERT A. HENDRIX, OF ALBERT LEA, MINNESOTA.

COMBINED CHURN AND BUTTER-WORKER.

1,117,569.

Specification of Letters Patent.

Patented Nov. 17, 1914.

Application filed September 10, 1913. Serial No. 789,078.

To all whom it may concern:

Be it known that I, HERBERT A. HENDRIX, a citizen of the United States, residing at Albert Lea, in the county of Freeborn and State of Minnesota, have invented certain new and useful Improvements in Combined Churns and Butter-Workers; and I do hereby declare the following to be a full, clear, and exact description of the invention, such as will enable others skilled in the art to which it appertains to make and use the same.

My invention relates to improvements in combined churning and butter workers and, to this end, it consists of the novel devices and combinations, of devices hereinafter described and defined in the claims.

In the accompanying drawings, which illustrate the invention, like characters indicate like parts throughout the several views.

Referring to the drawings: Figure 1 is a front end elevation of the improved churn and butter worker; Fig. 2 is a rear end elevation of the same; and Fig. 3 is a view principally in longitudinal, horizontal section, taken on the line $x^3 x^3$ of Fig. 1.

The numeral 1 indicates the drum shell and the numerals 2 and 3 indicate the drum heads. Axially located metallic plates 4 and 5 are secured, respectively, to the drum heads 2 and 3. Bolted to the drum head 2, on top of the plate 4, is an oil and gear casing 6 having a bearing sleeve 7. A spider bracket 8 is bolted to the plate 5 and is provided with a short trunnion 9 spaced outward from the drum head 3, as shown in Fig. 3. The axes of the bearing sleeve 7 and trunnion 9 are coincident with the axis of the drum. The drum is mounted for horizontal rotary motion on a pair of pedestals 10 and 11. The bearing sleeve 7 is loosely journaled on a fixed trunnion 12 bolted to the top of the pedestal 10 and the trunnion 9 is loosely journaled in a bearing box 13 bolted to the top of the pedestal 11. A flanged recessed bearing hub 14 extends axially through the drum head 2 and plate 4 and its flange overlaps said plate and is secured by bolts 15 to the drum head 2. Extended axially through the plate 5 and drum head 3 is a flanged tubular bearing hub 16 secured by bolts to the plate 5. Loosely journaled on the hubs 14 and 16 is an axial working roller 17 having secured to one end a recessed head 18 which is telescoped onto

the inner projecting ends of the hub 14. In the other end of the working roller 17 is a short trunnion 19 loosely journaled in the inner end portion of the hub 16. A plug 20 has screw threaded engagement with the outer recessed portion of the hub 16 and a coiled spring 21 is compressed between the outer end of the trunnion 19 and the screw plug 20. Axially alined with the working roller 17 is a short shaft 22, one end of which has screw threaded engagement with the head 18 and the other end of which is loosely journaled in a seat formed in the hub 14 and projects into the recessed portion of said hub. The intermediate portion of the shaft 22 is expanded to form a ground valve 23 seated in the inner end of the hub 14. The spring 21 yieldingly holds this valve 23 seated in the end of the hub 14 to form an oil tight joint between the casing 6 and the drum. Coöperating with the working roller 17 is a pair of relatively small eccentrically located working rollers 24. In the ends of these rollers 24 are secured recessed bearings 25 and 26. The bearings 25 are loosely journaled on flanged trunnions 27 secured to the head 2 and the bearings 26 are loosely journaled on the reduced inner ends of the hubs of stuffing boxes 28 secured to the drum head 3. It is important to note that the hubs of the stuffing boxes 28 and the hub 16 close openings in the plate 5 and head 3 of diameters sufficient to permit the working rollers 24 to be passed therethrough. The hubs of the stuffing boxes 28 are provided with flanges bolted to the plate 5. The working rollers 24 may be locked, at will, against rotation with respect to the drum, by means of headed lock pins 29 mounted, for endwise sliding movement, in the stuffing boxes 28. These lock pins 29 are formed with squared inner end portions that are slidably mounted in correspondingly formed seats in the hubs of the stuffing boxes 28 and are adapted to be moved into and out of sockets 31 formed in the bearings 26. The sockets 31 are also square in cross section end, when the squared portions 30 of the lock pins 29 extend into the sockets 31, lock the working rollers 24 to the hubs of the stuffing boxes 28.

Rotary motion is imparted to the drum by means of a tubular driving shaft 32 journaled in an axial perforation formed in the trunnion 12. Any suitable means, not shown, may be provided for driving the

shaft 32. The inner end of the driving shaft 32 extends into the casing 6 and has formed thereon a pinion 33. Telescoped onto the reduced inner end of the trunnion 12 is a sleeve 34 having integrally formed therewith a pair of oppositely extended radial gear supporting arms 35. Secured to the outer end portions of the arms 35 is a pair of laterally projecting headed studs 36 on each of which is journaled a relatively large intermediate spur gear 37 and a relatively small spur gear 38. A machine screw 39 locks the sleeve 34 to the trunnion 12 against rotation. The sleeve 34 affords a portion of the bearing for the sleeve 7.

The diametrically opposite spur gears 37 mesh with the pinion 33 and a large internal gear 40 formed on the periphery of the gear casing 6. Each pair of gears 37 and 38 is secured for common rotation by a pin 41 extending into the hubs of said gears. Slidably mounted on the squared end of the shaft 22, for rotation therewith, is a spur pinion 42 which meshes with the diametrically opposite spur gears 38. A shipper lever 43 is provided for sliding the spur gear 42 into and out of mesh with the spur gears 38. The shipper lever 43 is immediately fulcrumed to a bearing bracket 44 secured to the trunnion 12 and the short end thereof is bifurcated and its prongs embrace and are pivotally secured to a shipper collar 46 slidably mounted on the outer end portion of the driving shaft 32. The shipper collar 46 is connected to the spur pinion 42 by a plunger 47 slidably mounted, for endwise movement, in the driving shaft 32. The inner end of the plunger 47 is swiveled to the spur pinion 42 at 48 and the outer end thereof is secured to the shipper collar 46 by a pin 49 which works in a longitudinally extended slot 50 formed in the driving shaft 32. Oil in which the gears run is introduced into the gear casing 6 through a closed opening, not shown. Lifting flights 51 within the drum are provided for coöperation with the working rollers 17 and 24. The drum shell 1 is provided with the customary door opening, not shown, which is normally closed by a door 52.

What I claim is:—

1. The combination with a rotary body, of a driving shaft, a pinion on said shaft, an internal gear on said body, a gear support, and an intermediate gear journaled on said support and meshing with said pinion and internal gear.

2. The combination with a rotary drum, of an axial working roller loosely journaled in said drum and having a pinion secured for rotation therewith, a driving shaft, a pinion on said driving shaft, an internal gear on said drum, a gear support, an intermediate gear journaled on said support and meshing with the pinion on said shaft

and with said internal gear, and a gear secured for rotation with said intermediate gear and having its axis coincident with the axis thereof, said gear meshing with the pinion of said working roller.

3. The combination with a rotary drum, of an axial working roller loosely journaled in said drum and having a pinion secured for rotation therewith, a driving shaft, a pinion on said driving shaft, an internal gear on said drum, a gear support, an intermediate gear journaled on said support and meshing with the pinion on said shaft and with said internal gear, a gear secured for rotation with said intermediate gear and having its axis coincident with the axis thereof, said gear meshing with the pinion of said working roller, and means for moving the pinion on said working roller into and out of mesh with said gear, at will.

4. The combination with a rotary drum, of an axial working roller loosely journaled in said drum and having a pinion secured for rotation therewith, a driving shaft, a pinion on said shaft, an internal gear on said drum, a gear support, a pair of diametrically opposite intermediate gears journaled on said support and meshing with the pinion on said shaft and said internal gear, gears secured for rotation with said intermediate gears and having their axes coincident with the axes thereof, and means for moving the pinion on said working roller into and out of mesh with said gears, at will.

5. The combination with a rotary body and means for supporting the same, including a fixed tubular trunnion having its axis coincident with the axis of said body, a gear casing journaled on said trunnion and rigidly secured to one of the heads of said body and supporting the same, an internal gear on said casing, a driving shaft journaled in said trunnion, a pinion on said driving shaft, a gear support rigidly secured to said trunnion, and an intermediate gear journaled on said support and meshing with said pinion and internal gear.

6. The combination with a rotary drum and means for supporting the same, including a fixed tubular trunnion having its axis coincident with the axis of said drum, of a gear casing, affording an oil chamber journaled on said trunnion and rigidly secured to one of the heads of said drum and supporting the same, an internal gear on said casing, a driving shaft journaled in said trunnion, a pinion on said driving shaft, a gear support rigidly secured to said trunnion, and a pair of diametrically opposite intermediate gears journaled on said support and meshing with said pinion and internal gear.

7. The combination with a rotary drum, of an axial working roller loosely journaled in said drum and having a pinion secured for

rotation therewith, a fixed tubular trunnion having its axis coincident with the axis of said drum, a gear casing journaled on said trunnion and secured to one of the heads of said drum, an internal gear on said casing, a driving shaft journaled in said trunnion, a pinion on said shaft, a gear support secured to said trunnion, a pair of diametrically opposite intermediate gears journaled on said support and meshing with said internal gear and the pinion on said shaft, gears secured

for rotation with said intermediate gears and having their axes coincident with the axes thereof, and means for moving the pinion on said working roller into and out of 15 mesh with said gears, at will.

In testimony whereof I affix my signature in presence of two witnesses.

HERBERT A. HENDRIX.
